UNITED STATES PATENT OFFICE.

WALTER KIESER, OF CHARLOTTENBURG, GERMANY, ASSIGNOR TO GENERAL ELECTRIC COMPANY, A CORPORATION OF NEW YORK.

CENTRIFUGAL PUMP AND AIR-COMPRESSOR.

1,115,942.

Specification of Letters Patent.

Patented Nov. 3, 1914.

Application filed July 21, 1912. Serial No. 780,375.

To all whom it may concern:

Be it known that I, WALTER KIESER, a citizen of the Swiss Republic, residing at Charlottenburg, Germany, have invented 5 certain new and useful Improvements in Centrifugal Pumps and Air-Compressors, of which the following is a specification.

This invention relates to centrifugal pumps and air compressors, and its object is 10 to prevent excessive wear of the casing by the impact of the water thrown off by the rotary impeller. In that type of centrifugal air pump in which the air is driven by water slugs or pistons thrown by the impeller into 15 a stationary set of discharge vanes or directing buckets, the water issuing from the passages between said discharge vanes or directing buckets impinges upon the walls of the casing forming the pressure chamber from 20 which the delivery pipes for air and water lead off. Even if the jets of fluid are more or less deflected from a direct course, the walls of the casing are subjected to great 25 wear by the friction of the water. The present invention aims to avoid this difficulty by providing a water cushion upon which the jets strike before the water and air are led into the pressure chamber from which they pass to their separate delivery pipes. I prefer 30 to establish this water cushion by means of a removable protecting ring, U-shaped in cross section, arranged concentric with the directing ring and receiving the water issuing therefrom. The water and air escape 35 from said protecting ring into the pressure chamber through a narrow gap, whose cross sectional area is a trifle smaller than that of the discharge passages in the directing ring, so that the escape of fluid from the protecting 40 ring is restricted and the water chamber in the protecting ring is kept full, thereby forming a water cushion upon which the jets impinge upon their exit from the directing passages. By this means, the flow 45 of the water and air to the pressure chamber is effected without impact upon the walls of the casing, and rapid wear of the casing is avoided. The protecting ring, also, is subject to little wear, but in case of necessity it can be replaced by a new one.

In the accompanying drawing, Figure 1 is a section of a portion of a centrifugal pump and air compressor embodying my invention, and Fig. 2 is a detail section showing the protecting ring on a larger scale.

The pump illustrated is of the horizontal type, but my invention is equally well applicable to upright pumps. The rotary impeller 1 is of any suitable construction, and receives water from the intake 2, delivering 60 it radially into the stationary directing ring 3 whose vanes form directing passages 4 to convey the fluid to the pressure chamber 5. The air to be compressed enters through the inlet 6 and is entrained by the water in the discharge passages of the ring 3, being carried through between slugs or pistons of water.

Surrounding the directing ring 3 is a protecting ring 7, which is U-shaped in cross 70 section and is placed with its flanges toward the ring 3. The protecting ring is preferably seated in an annular groove in the casing 8, where it is removably secured by screw-threaded studs 9. The flange 7' of 75 the ring 7 does not quite touch the periphery of the directing ring 3, which is preferably widened, as shown. This leaves a narrow annular gap 10 between the rings, through 80 which the fluid thrown into the protecting ring can escape into the pressure chamber 5 of the pump. The total cross-sectional area of the gap 10 is a little less than that of the discharge passage in the directing ring, so that the gap sets up a slight back pressure 85 which serves to keep the protecting ring full of water all the time. This body of water acts as a cushion to receive the streams of water and air coming through the discharge 90 passages 4 in the directing ring, and thus all danger of injurious wear on the protecting ring is practically wholly eliminated. Should it happen that the ring does become worn, it can be easily removed and a new 95 one inserted.

In accordance with the provisions of the patent statutes, I have described the principle of operation of my invention, together with the apparatus which I now consider to represent the best embodiment thereof; but 100 I desire to have it understood that the apparatus shown is only illustrative, and that the invention can be carried out by other means.

What I claim as new and desire to secure by Letters Patent of the United States, is,— 105

1. The combination with a centrifugal air compressor having a rotary impeller and a stationary directing ring concentric therewith, of means concentric with the directing ring for receiving the water therefrom and 110

retarding its escape so as to form a water cushion.

2. The combination with a centrifugal air compressor having a rotary impeller and a stationary directing ring concentric therewith, of means for confining an annular body of water concentric with said directing ring and receiving the streams of fluid issuing from said ring.
- 5 3. The combination with a centrifugal air compressor having a rotary impeller and a stationary directing ring concentric therewith, of a U-shaped protecting ring concentric with said directing ring.
- 10 4. The combination with a centrifugal air compressor having a rotary impeller and a stationary directing ring concentric therewith, of a U-shaped protecting ring concentric with said directing ring.
- 15

with, of a U-shaped protecting ring concentric with said directing ring, and means for restricting the escape of fluid from said protecting ring.

20 5. The combination with a centrifugal air compressor having a rotary impeller, and a stationary directing ring concentric therewith, of a U-shaped protecting ring concentric with said directing ring, one flange of said protecting ring leaving a narrow annular gap between itself and the directing ring.

25 In witness whereof, I have hereunto set my hand this 9th day of July, 1913.

WALTER KIESER.
